(57) CLAIM

The ornamental design for a tea infuser, as shown and described.

DESCRIPTION

FIG. 1 is a perspective view showing the new, original, and ornamental design of a tea infuser;

FIG. 2 is a left elevation view thereof, the right side being a mirror image;

FIG. 3 is a rear elevation view thereof;

FIG. 4. is a front elevation view thereof;

FIG. 5. is a top plan view thereof; and,

FIG. 6 is a bottom plan view thereof.

The dash-dash and half circle broken lines shown in FIG. 1 and FIG. 5 on the top area of the tea infuser represent portions of the tea infuser and form no part of the claimed design.
